CHARLES G. ETTE, OF ST. LOUIS, MISSOURI, ASSIGNOR TO ETTE INVESTMENT COMPANY, OF ST. LOUIS, MISSOURI, A CORPORATION OF MISSOURI.

TROLLEY-WIRE SUPPORT OR HANGER.

No. 909,569.

Specification of Letters Patent. Patented Jan. 12, 1909.

Application filed May 4, 1908. Serial No. 430,768.

To all whom it may concern:

Be it known that I, CHARLES G. ETTE, a citizen of the United States, residing at St. Louis, Missouri, have invented a certain new and useful Improvement in Trolley-Wire Supports or Hangers, of which the following is a full, clear, and exact description, such as will enable others skilled in the art to which it appertains to make and use the same, reference being had to the accompanying drawings, forming part of this specification, in which—

Figure 1 is a side elevation of a trolley wire support constructed in accordance with my invention; Fig. 2 is a vertical sectional view taken on approximately the line 2—2 of Fig. 1; Fig. 3 is a detail perspective view of the insulating member and a portion of the shank that carries the clamping jaws; and Fig. 4 is a horizontal sectional view taken through the shanks of the clamping jaws.

This invention relates to supports or hangers for trolley wires, and particularly to the trolley supports used in systems in which the trolley wire is sustained in operative position by means of guide wires that extend transversely of a street and are connected to poles located at opposite sides of the street.

The main object of my invention is to provide a trolley wire support comprising few parts and which can be manufactured at a low cost.

Another object of my invention is to provide a trolley wire support in which the jaws that clamp the trolley wire are perfectly insulated from that portion of the support which is connected to the guide wire that sustains the support. And still another object of my invention is to provide a trolley wire support comprising a part that is adapted to be connected to a guide wire that sustains the support, members for clamping a trolley wire, and a removable part which sustains said clamping members and also insulating material that insulates the clamping members from the part that is connected to the guide wire.

Other objects and desirable features of my invention will be hereinafter pointed out.

Referring to the drawings which illustrate the preferred form of my invention, I design-

nates an inverted cup-shaped member, the top of which is provided with a dome or crown 2 having integral lugs or hooks 3 which are adapted to engage a guide wire A 55 that extends transversely of a street or road.

The clamping members which engage the trolley wire B consist of two jaws 4 and 5 that are carried by a shank 6 which projects into the cup-shaped member 1, said shank being provided with a head that consists of two laterally projecting ring-shaped flanges 7.

An insulating member, which preferably consists of two or more blocks 8 of some suitable insulating material, is interposed 65 between the flanges 7 on the shank 6, and said insulating blocks conform to the interior of the cup-shaped member 1 so that they will fit snugly inside of same, as shown in Fig. 2. The insulating member thus 70 forms the supporting means for the shank 6 which carries the clamping jaws, and said insulating member is sustained and locked in operative position by means of a movable ring-shaped member 9 provided with ex- 75 ternal screw-threads that interlock with the screw-threads 10 on the interior of the inverted cup-shaped member 1. The ring-shaped locking member 9 is preferably pro- 80 vided at its upper edge with a flange 11 that provides an extended supporting surface for the insulating member and clamps said insulating member against the inside face of the top of the inverted cup-shaped member 1, as shown in Fig. 2. Said locking 85 member 9 is also preferably provided at its lower end with a flared skirt 9a which tends to shed water from the clamping jaws 4 and 5.

In the construction herein shown the 90 shank 6 is provided with a half-round screw-threaded portion 4a and an integral clamp jaw 4 and the co-operating movable clamp- 95 ing jaw 5 consists of a separate part that is provided with a half-round shank 5a having external screw-threads. A clamping nut 12 surrounds the screw-threaded shanks of said jaws for forcing said jaws together so that they will firmly clamp the trolley wire B interposed between them, and the shank 6 100 is provided with a longitudinally extending rib 13 that fits in a recess in the shank of

the movable jaw and a laterally projecting lug 13^a that extends through a slot in said jaw so as to prevent the movable jaw from moving laterally or vertically relatively to the integral jaw 4 on the shank.

The clamping jaws may be of any preferred construction and can be designed to coöperate with either a round trolley wire or a grooved trolley wire. All of the parts of my improved trolley wire support are formed of cast metal, preferably malleable iron, and the only machine-work that is required in the manufacture of the device is cutting the threads 10 on the interior of the inverted cup-shaped member 1 and on the exterior of the ring-shaped locking member 9. The dome 2 in the top of the member 1 prevents the upper end of the shank 6 from contacting with the top of said member, and the blocks 8 of insulating material hold said shank 6 spaced away from the sides of said member so that the clamping jaws which engage the trolley wire are perfectly insulated from that portion of the support which is connected to the guide wire, thereby preventing the current in the trolley wire from passing into the guide wire and thence into the poles to which said guide wire is connected.

The parts which form my improved trolley wire support can be assembled quickly, for a single member; namely, the locking ring 9, operates to clamp the insulating member in position and also sustain the jaws which clamp the trolley wire.

The flanges 7 on the shank 6 between which the insulating member is interposed prevent the clamping jaws from moving upwardly or downwardly, and as the insulating member has an extended bearing surface on said shank it holds the shank rigid and prevents the clamping jaws from moving laterally.

While the device herein illustrated and described is intended to be used principally for supporting a trolley wire, it will, of course, be obvious that it could be used for other purposes without departing from the spirit of my invention.

The trolley wire supports that have heretofore been in use comprised a great number of screw-threaded parts that would rattle and work loose after the device had been in use for a short period. My improved device overcomes this objectionable feature as it comprises very few parts. The split insulating member which is arranged between the flanges 7 on the shank 6 can be inserted easily and said shank and insulating member are so formed that the shank 6 can swivel in said insulating member and thus permit the trolley wire to assume any angle relatively to the support.

Having thus described my invention, what I claim as new and desire to secure by Letters Patent is:

1. A device for the purpose described, comprising an inverted cup-shaped member, a removable device arranged inside of said member and detachably connected thereto, an insulating member mounted inside of said cup-shaped member and resting upon said removable device, and a line-holding device comprising a shank passing through said insulating member and provided with a head that rests upon the upper surface of said insulating member; substantially as described.

2. A device for the purpose described, comprising an inverted cup-shaped member provided with a dome-shaped top, a shank projecting into said member and provided with laterally projecting flanges and means for holding a wire, an insulating member arranged inside of said cup-shaped member and interposed between the flanges on the shank for holding shank out of engagement with the cup-shaped member, and means for clamping said insulating member in position; substantially as described.

3. A device for the purpose described, comprising a one-piece inverted cup-shaped member, a shank projecting into said member and provided with clamping jaws, flanges on said shank, an insulating member arranged inside of said inverted cup-shaped member and interposed between said flanges, and a removable device screwed into the lower end of said inverted cup-shaped member for retaining said insulating member in position; substantially as described.

4. A device for the purpose described, comprising an inverted cup-shaped member provided with lugs which are adapted to engage a guide wire, an insulating member arranged inside of said cup-shaped member, a clamping ring screwed into said cup-shaped member for holding said insulating member in position, a shank passing through said insulating flange or member and provided at its upper end with a head that rests on said insulating member, and means carried by said shank for holding a trolley wire; substantially as described.

5. A device for the purpose described, comprising an inverted cup-shaped member formed of malleable iron and having a dome-shaped top which is provided with integral lugs for engaging a guide wire, a sectional insulating member arranged inside of said cup-shaped member, a shank passing through said insulating member and provided with a head which rests upon the upper side of said insulating member in the hollow space of said dome-shaped top, clamping jaws carried by said shank, a ring screwed into said

cup-shaped member and provided with a flared skirt which sheds water from said clamping jaws, and a flange on the upper edge of said ring which clamps the insulating member against the outer edge portion of the top wall of the cup-shaped member; substantially as described.

In testimony whereof I hereunto affix my signature in the presence of two witnesses, this twenty-ninth day of April 1908.

CHARLES G. ETTE.
